UNITED STATES PATENT OFFICE

2,677,907

ELECTRIC IRON

Dale C. Gerber, North Canton, and Elmer C. Binggely, Canton, Ohio, assignors to The Hoover Company, North Canton, Ohio, a corporation of Ohio

Application July 26, 1950, Serial No. 176,021

3 Claims. (Cl. 38—89)

1

This invention relates to electric sadirons and more particularly to a novel arrangement and construction of the operating handle and the temperature control dial with respect to the remainder of the iron.

To be effective and to perform the ironing task speedily, an electric iron should operate at a high temperature range, it being understood that this range includes the relatively lower temperatures for certain fabrics such as rayon and silk and the relatively higher temperatures for linens and woolens. Of necessity, these operating temperatures are maintained in a zone very close to the operator's hand. Many attempts have been made to confine these high temperatures to the immediate vicinity of the sole plate and to maintain a cool zone thereabove for the comfort of the operator. Typical of the various expedients resorted to is the use of heat insulating material between the sole plate and the cover shell; spaced and air ventilated horizontal fins between the sole plate and the operating handle; and power driven fans to circulate cooling air in the area about the handle. While these expedients have met with some success, they are all subject to numerous disadvantages including complexity of construction, high cost, increased weight, service and maintenance difficulties.

Another deficiency of prior constructions is the hazard to the user from severe burns unavoidably inflicted while using the iron. Such burns are obtained in the majority of instances either when the operator grasps or removes her hand from the handle or attempts to adjust the temperature control and, in so doing, touches the hot cover shell.

It is an object of the present invention to provide a simple, inexpensive, rugged and novel construction which overcomes the aforementioned and other disadvantages of prior electric irons.

More specifically, it is an object to provide an iron in which the handle and temperature control are designed to perform their usual functions and additionally to divide the iron into a lower high temperature zone and an upper cool zone.

Another object is to provide an iron with a handle grip which is heat insulated from the iron body without the use of parts in addition to those heretofore used in constructing irons lacking the advantageous features of this invention.

A further object is to provide a new and improved temperature control dial affording great convenience to the operator, and which is not only an effective heat barrier for the handle grip but which is designed to provide a positive safeguard against burning the operator's fingers.

2

Still another object is to provide a novel temperature control dial having a new and more convenient arrangement of the indicia, which requires less effort to adjust and which can be manipulated with equal convenience from any adjusted position and without need for removing the hand from the handle grip.

Numerous other objects and advantages of the invention will become apparent from the following specification and illustrative drawings in which:

Figure 1 is a side view of an electric sadiron incorporating the invention;

Figure 2 is a top plan view of the iron;

Figure 3 is a vertical sectional view;

Figures 4 and 5 are side and top views respectively of a second embodiment of the invention.

This application is a continuation-in-part of our co-pending application for Letters Patent, Serial No. 695,394, filed September 7, 1946, for improvements in Electric Irons, which application has since been abandoned in favor of this application.

One preferred embodiment of the invention is illustrated in Figures 1 to 3. The iron comprises the usual sole plate 10, a cover shell 11 and an operating handle 12. The operating handle, preferably made in one piece, includes a grip 13 supported by a forward leg 14 and a rear leg 15. The large diameter temperature regulator dial 16 lies in closely spaced relation to the top of shell 11 and will be described in greater detail below. The usual electric service cord 17 is preferably supported by means of the usual strain relief in one face of rear handle leg 15 such as in the position shown in Figure 2. The cover shell 11 extends rearwardly beyond the heel of the sole plate as indicated at 18 and its rearmost end cooperates with the rear end 19 of the handle grip to provide a broad base rest for the iron when it is not in use. A cover plate 20 is removably secured to the under side of projecting end 18 of the cover shell and permits access to the internal end of the service cord, as will be readily apparent from Figure 3.

While the internal construction of the iron may take many forms, one particularly simple and rugged construction is illustrated in detail in Figure 3. A generally U-shaped resistance heating element 21 is imbedded in the sole plate and its terminals are positioned adjacent the heel of the sole plate in a convenient position to be connected in circuit with the temperature regulator and the service cord.

A thermostatic temperature regulator device 22 is supported on the top surface of the sole

plate by a mounting screw 23. The bimetallic thermal element 24 is located as close as possible to the sole plate and supports an insulator button 25 which abuts the upper leaf 26 of the control switch. The other leaf 27 of the switch underlies leaf 26. The position of leaf 27 relative to leaf 26 can be adjusted from the control dial 16. This is accomplished by means of a threaded shaft 28 which passes through a nut 29 carried by stationary arm 30 of the control assembly. The lower end 31 of shaft 28 passes through an enlarged opening in leaf 26 of the switch and bears against the upper side of leaf 27. Lug 32 carried by shaft 28 and lug 33 carried by nut 29 serve to limit movement of shaft 28 between a position in which the switch is open regardless of the temperature of the iron and a limiting high temperature position of the regulator. Dial 16 is removably secured to the upper end of shaft 28 as by set screw 34 which is accessible through a notch 35 in the rim of dial 16.

The forward end of the cover shell 11 is secured to the sole plate as by a threaded stud 36 and screw 37, while the rear end is likewise secured in place by a screw 38 mating with member 39 which is rigidly fixed to the heel of the sole plate.

Handle 12 is preferably made as a one-piece molded plastic member and of a material having very low heat conductive properties. The forward and rear legs are provided with large area bases contoured to conform to the adjacent periphery of the top of the cover shell and also to embrace the rim of the regulator dial. The lower ends of the legs are cavitated to reduce the weight and the heat conducting capacity of the legs. A lug 40 is secured in the cavity of the front leg by a screw 41 while the opposite end of the lug is secured to the cover plate by a screw 42. A similar lug 43 has its top end secured to the top of the rear leg cavity, as by screw 44, while its lower end is shown as riveted to the top of the cover shell.

The enclosed end of the service cord extends through a large opening in the rear top portion of the cover shell down into the space closed by cover plate 20. One lead of the cord is connected to heating element 21 and the other lead is connected by wire 45 to lead 26 of the thermostatic switch 22. A third lead, not shown, connects switch leaf 27 with the other end of the heating element.

As in the case of the operating handle, the thermostatic regulator dial 16 is made of molded plastic material having very low heat conductive properties. This dial has a diameter which extends from side to side of cover shell 11 and which is substantially co-extensive with the lower side of handle grip 13, as clearly appears from Figures 1 to 3. Projecting upwardly and outwardly from the rim portion of the dial are a plurality of closely spaced projections or ribs 46. These projections are preferably arranged in a continuous circle. It will be noted that the ribs are so contoured and positioned with respect to the grip 13 as to be conveniently grasped or contacted by the sides of the thumb and fingertips as the palm of the operator's hand rests on the grip. Thus, the operator's fingers will contact the projection on one side of the dial at one side of the iron while the thumb will grip the dial projections on the opposite side of the iron.

It will also be observed from the drawings that the dial is provided with a horizontally extending flange 47 which extends radially beyond the pro-

jections 46 and serves a plurality of functions. One of these is to provide a rest for the ends of the operator's fingers while she is adjusting the dial. It also serves as a guard and safety device for preventing the operator from accidentally contacting the hot cover shell while adjusting the temperature regulator. Still another important function of flange 47 is to support large-type indicia which are readily readable by the operator at a distance from the iron and by means of which she can readily determine the particular temperature setting of the dial. Being at the extreme periphery of the dial, the indicia are directly opposite the stationary control indicia 48 which, as clearly shown in Figure 2, are located on the base of the front handle leg at a point offset from the center line of the iron so as to be readily visible to the operator. Since indicia 48 are located to one side of the handle grip, the operator can view them from her normal operating position clearly and without interference from the handle or from her fingers while grasping the grip.

It will therefore be readily appreciated that by this novel arrangement, the operator always looks to one point when checking the position of the temperature regulator or when desiring to shift it to a new position. This location is, of course, the area in the vicinity of the stationary indicia 48. As shown in Figure 2, the dial is in the "off" position in which the thermostatic switch is open regardless of the temperature condition of the iron. If the operator desires to iron silk, she observes the area adjacent indicia 48 and rotates the dial clockwise until the work "Silk" on flange 47 is opposite dot 48. This adjustment is most conveniently accomplished while the operator has the palm of her hand resting on the grip and while she is utilizing her thumb and fingers to grasp projections 46 on the opposite sides of the dial to rotate it in the direction desired.

It is also to be noted that flange 47 projects sufficiently to overlie the clearance gap between the bases of the handle legs and the lower rim portion of the dial. This projection serves to prevent direct radiant heat from the top of the cover shell being reflected to the handle grip and aids materially in maintaining the handle grip at a comfortable low operating temperature.

By reference to Figure 3, it will be noted that a spider spring 49 is interposed between the top of shell 11 and the under side of dial 16. This spring provides a resilient support for the dial and protects the temperature regulator against injury by the application of too much pressure to one side of the dial.

Another embodiment of the invention illustrated in Figures 4 and 5 is generally similar to that just described and differs only in the design of the temperature regulator dial and the bases of the handle legs. The same or similar elements to those of the first described embodiment are indicated by like reference characters distinguished by a prime. The internal construction of the iron is identical with the first described embodiment. As clearly evident from Figures 4 and 5, the temperature control dial is slightly smaller in diameter due to the omission of the flange extending beyond projections 46'. It will be noted that the dial indicia are carried inside the projections 46' and as close to the periphery of the dial as is conveniently possible. Since the dial does not extend laterally beyond the top edge portions of cover shell 11' it is un-

necessary to provide the shell with side bulges underlying the projecting portion of the dial as is true of the first described embodiment.

Another distinction of the second embodiment is that the bases of the handle legs project further toward the center of the iron in order to closely embrace the rim of the smaller diameter dial. These bases, together with the dial, overlie the entire top surface of the cover shell and provide a very efficient heat barrier against the transmission of heat from the sole plate and cover shell to the grip of the operating handle.

As is clearly evident from Figure 4, the finger contacting edges of projections 46' are spaced at a considerable distance above the top of the cover shell and this fact, together with the large diameter of the dial, renders it difficult if not impossible for the operator to contact the hot cover shell with the fingertips when adjusting the dial. This is especially true if the operator keeps the palm of her hand on the top of the grip while making the adjustment.

From the foregoing detailed description of two illustrative embodiments of the invention it will be readily apparent that an unusually simple and rugged construction has been disclosed having many unique features and in which each of the several principal parts has multiple, mutually cooperative functions. Both the operating handle and the temperature regulator dial, being made of heat insulating material, cooperate with one another and with the remaining iron structure to provide an unusually effective heat barrier isolating the high temperatures of the sole plate from the operating zone spaced immediately above the top of the cover shell. The spacing of the handle legs at the under side of the dial slightly above the top of the cover shell together with the small cross-sectional area of the metallic supporting elements connecting the handle and the dial to the remainder of the iron additionally contribute to the heat insulating characteristics of the construction and the ability of the novel arrangement to separate the iron into a relatively high temperature zone below the top of the cover shell and a relatively cool and comfortable operating zone above the cover shell.

It is also obvious that the operator may regulate the temperature control very quickly without any danger of burning her hand and without removing her hand from the handle grip.

While we have shown and described but two embodiments of our invention, it is to be understood that these embodiments are to be taken as illustrative only and not in a limiting sense. 53 We do not wish to be limited to the particular structures shown and described, but to include all equivalent variations thereof except as limited by the scope of the claims.

We claim:

1. The combination with an electric sad iron of the type having a sole plate, a heating element, a cover shell for said sole plate, an adjustable thermostatic temperature regulator connected in

circuit with said heating element, of an operating handle for said iron having a grip supported between forward and rear legs, a control dial for said temperature regulator, said dial being formed primarily of heat insulating material and having a diameter extending substantially from side to side of said cover shell and from the inner face of said rear handle leg to the inner face of said forward handle leg and underlying substantially the full length of the lower face of said grip, the peripheral area of said dial being provided with an annular row of closely spaced elements projecting upwardly from the upper surface of the body of said dial and said handle legs being constructed and arranged with large area bases shaped to embrace the adjacent rim portions of said dial and to cooperate therewith to overlie substantially the entire top area of said cover shell to provide a substantially continuous heat barrier between said shell and said handle grip.

2. In an electric sad iron, an iron body, a handle attached to said body, a control dial above the top of said body for adjusting a thermostat shaft in said body, said handle having a hand grip and spaced supporting legs for positioning said hand grip above said body, said supporting legs having large area bases adjacent to the top of said body and projecting toward each other and terminating for their full width in arcuate faces spaced from each other to substantially define therebetween a circular opening for said control dial, said dial disposed in said opening between said arcuate faces and above the top of said body and having its peripheral edge contiguous to said arcuate surfaces, said handle bases and control dial cooperating to overlie substantially the entire top area of said body and being formed of heat insulating material to provide a substantially continuous heat insulating barrier which covers the top of said iron body between said handle bases to protect the hand grip from heat emanating from said iron body.

3. An electric sad iron as defined in claim 2 wherein said control dial has indicia distributed along the peripheral area thereof, a stationary indicia mark on said iron adjacent the rim of said dial, said stationary indicia being at the forward rim of said control dial and laterally offset to one side of said hand grip so as to be visually observable by the operator from a vantage point substantially directly above said hand grip.
